UNITED STATES PATENT OFFICE.

LEM A. SMITH, OF ENGLEWOOD, NEW JERSEY.

ELECTRIC SPARKING IGNITER FOR EXPLOSIVE-ENGINES.

No. 826,123.

Specification of Letters Patent.

Patented July 17, 1906.

Application filed April 16, 1904. Serial No. 203,430.

To all whom it may concern:

Be it known that I, LEM A. SMITH, a citizen of the United States, residing in Englewood, in the county of Bergen and State of New Jersey, have invented certain new and useful Improvements in Electrical Sparking Igniters for Explosive-Engines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to internal-combustion engines of the type wherein the ignition of the fuel in order to produce the explosions is caused by compressing the fuel to the ignition-point. In one class of such engines this compressing is effected by means auxiliary to the main cylinder and piston, the resultant flame being directed into the main cylinder to ignite the main body of fuel therein, and thus produce the explosions which do the work of actuating the piston. In this case the engine is readily started by turning it over two or three times by hand or other external means until the explosions in the auxiliary cylinder begin to occur. In another class of these engines the explosions in the main cylinder are produced without auxiliary ignition by causing the piston to compress the fuel to the ignition-point on the back stroke. In this case the engine is started by employing heat externally in order to bring the fuel to the ignition-point, after which of course the engine is left to work itself. (See United States Patent No. 313,922 and *The Gas and Oil Engine*, pp. 420—423, D. Clerk, John W. Wiley & Sons, publishers, New York, 1902.). It is to this class of engines that my invention particularly relates. In common practice in this specific class of engines the auxiliary heating is accomplished by applying a flame at a relatively small, and hence quickly-heated, chamber which communicates with the main cylinder, but holds the bulk of a part of the fuel relatively detached from the main body thereof in the cylinder.

The principal object of my invention is to provide a universally-available internal-combustion engine in which kerosene, as one of

the cheapest, generally-obtainable, and safest oils, can be used.

The use of kerosene-oil as the source of power to operate engines generally has been limited. It is found impracticable to employ it in the type of engine where an electric "sparker" is employed to effect the ignition, partly because not enough heat is thereby generated to cause explosions and partly because the points of the sparker sooner or later become carbonized by the oil and cease to operate. In types of engines where the ignition is not produced by the electric sparker; but by intermittent flame injections, the mechanism at once becomes one which makes its adoption as an engine adaptable for general work prohibitive on account of its inherent complexity, and in that type of engines where the auxiliary igniting is only resorted to for the purpose of starting the engine its employment has been restricted by its environment, for in mining machinery, for instance, it is not available on account of the danger of explosions in the mine following on the use of an exposed flame or other means giving a heat sufficient to bring the fuel in the engine to the explosion-point.

The invention will be found fully illustrated in the accompanying drawings, wherein Figure 1 is a view in front elevation of an internal-combustion engine constructed after the principles of my invention. Fig. 2 is a side view of said engine, showing its cylinder and certain accessories thereof in vertical section; and Fig. 3 is an enlarged view showing the upper portion of said cylinder and certain accessories thereof in vertical section.

In said drawings, *a* is the cylinder, and *b* the piston, the former having a fuel-supply *c* and the usual exhaust and controlling means therefor, (shown at *c'*). The cylinder stands vertically on a base *d*, which is supported by a pedestal *e*, in which latter is journaled a shaft *f*, which is driven from the piston *b* through a crank *g* and pitman *h*.

The cylinder is shown as of the type (illustrated in the aforementioned references) having a surmounting extension-chamber *i* attached. This chamber forms an easily-heated adjunct of the cylinder and is therefore readily adapted for starting the engine by first heating the fuel inclosed by it and for maintaining the explosions by becoming sufficiently heated by each explosion to cause

the succeeding explosion upon proper conditions of the fuel as to mixture and compression.

In carrying out the object of my present invention I employ means for forming a voltaic arc in the cylinder. I will now describe this means with reference particularly to Fig. 3. In this figure *j* and *k* are positive and negative carbons, respectively. These are fitted into sockets *l* in the ends of adjusting-screws *m*, being held therein by pins *n*, which transversely penetrate the socket portions of the screws and the carbons. The screws *m* are tapped into metallic thimbles *o*, and these in turn are set into tubular insulating-shells *p*, one end of each of which, except for an axial opening *q*, through which the carbon projects and wherein the carbon is guided, is closed.

The insulators *p*, carrying the carbons, their adjusting-screws, and the thimbles *o* in the manner above described, are screwed into the cylinder at diametrically opposite points, so that the carbons may be brought point to point alined. It is preferable in securing this assemblage of the parts to form a transverse hole *r* through the cylinder-head, tapped, as at *s*, at its outer ends to receive the screw-threading *t* on the insulators. In the engine shown in the drawings, where the extension-chamber *i* is included in its construction, the carbon-points will stand in a passage *u*, whereby communication between the cylinder and the interior of the extension-chamber is afforded. Thus arranged the carbons are disposed out of the cylinder-space, allowing the piston full play from one end to the other thereof. This arrangement also brings the carbons into close disposition to metallic surfaces, so that the latter coat with the carbons, by becoming heated, to raise the temperature of the fuel to that condition which upon sufficient compression is essential to the explosion. A metallic baffle-plate *v* is arranged in proximity to the carbon-points and relatively between them and the point where the fuel is discharged into the cylinder. This will act to not only prevent the fuel from being directly impelled on the carbons, but will tend to bring the air and vapor into a more homogeneous mixture before coming into ignition proximity to the carbons. It moreover increases the area of metallic heat-storing surface which it is desired, for the reason above mentioned, to bring in close disposition to the carbon-points.

The arrangement above described and shown in the drawings involves an extension-chamber attached to the main cylinder, an igniting means located in a passage leading thereto, and a baffle-plate arranged between the igniting means and the fuel-admitting means and close to the former; but it will be understood that my invention contemplates

any arrangement in which the igniting means is located in a recess forming a part of the explosion-chamber, but set apart from the space of the latter in which the piston plays and having its wall portion adapted to be more quickly heated than the remaining wall portion of the inclosure and in which a baffle-plate is located between the igniting means and the fuel-admitting means and close to the former.

In order that the engine may store up its own source of electrical energy necessary for producing the arc at the carbons, a dynamo *w* is shown mounted on the pedestal *e* as driven by friction from one of the wheels *x* on the shaft *f* of the engine, such dynamo being adapted to be connected with a storage battery *y* through wiring *z* 1, comprising, with the elements of said battery and the dynamo, an electrical circuit. By a switch 2 in the wiring *z* this circuit may be opened or closed. The portion of wiring *z* between the switch and the battery has a branch 3, which leads to one of the thimbles *o*, to which it is electrically connected. 4 is another wire, which is connected at one end to the thimble *o* for the other carbon and extends to a point near wiring 1, to which it may be connected by a switch 5 when necessary. If desired, a lighting or other service circuit 6 may form a branch of the circuit in which wires 3 4, the storage battery, and the carbons are included. When the switch 2 is closed and the switch 5 open, the dynamo when driven will store up the electrical energy in the storage battery. Upon opening switch 2 and closing switch 5 the energy thus stored up may be used to form the arc between carbons *j* and *k*.

Having thus fully described my invention, what I claim as new, and desire to secure by Letters Patent, is—

1. The combination, with the explosion-inclosure and a piston arranged therein, said inclosure having a recess set apart from the space therein in which the piston plays, of an electric igniting means arranged in said recess, means for admitting fuel into the cylinder, and a baffle-plate arranged between said igniting means and the fuel-admitting means and close to the former, substantially as described.

2. The combination of a cylinder, a piston arranged therein, an extension-chamber attached to said cylinder, said cylinder having a recess forming a passage communicating with the interior of said chamber, an electric-arc-forming means arranged in said passage, means for admitting the fuel into the cylinder, and a baffle-plate arranged between said arc-forming means and the fuel-admitting means and close to the former, substantially as described.

3. The combination of a cylinder, a piston arranged therein, an extension-chamber attached to said cylinder, said cylinder having

a recess forming a passage communicating with the interior of said chamber, an electric-arc-forming means arranged in said passage, means for admitting the fuel into the cylinder, and a metallic baffle-plate arranged between said arc-forming means and the fuel-admitting means and close to the former, substantially as described.

In testimony that I claim the foregoing I have hereunto set my hand this 8th day of April, 1904.

LEM A. SMITH.
